UNITED STATES PATENT OFFICE.

ANTON MERZ, OF CHICAGO, ILLINOIS.

DESIGN FOR A PERCOLATOR.

46,776.

Specification for Design.

Patented Dec. 15, 1914.

Application filed November 17, 1913. Serial No. 801,547. Term of patent 3½ years.

To all whom it may concern:

Be it known that I, ANTON MERZ, a citizen of the United States, and a resident of the city of Chicago, in the county of Cook and State of Illinois, have invented a new, original, and ornamental Design for Percolators; and I do hereby declare that the following is a specification thereof, reference being had to the accompanying drawing, forming a part hereof, in which the figure is a perspective view of a percolator showing my new design.

I claim:—

The ornamental design for a percolator as shown.

In testimony whereof I have hereunto set my hand in the presence of two subscribing witnesses on this fifteenth day of November, 1913.

ANTON MERZ.
